UNITED STATES PATENT OFFICE

JASPER B. WILLSEA AND THOMAS A. KENNEDY, OF ROCHESTER, NEW YORK, ASSIGNEES
TO WILLSEA WORKS, OF ROCHESTER, NEW YORK, A CORPORATION OF NEW YORK

FURNACE

Application filed August 18, 1930. Serial No. 476,120.

This invention relates to improvements in furnaces, and especially to that kind of furnace used for heating foundry ovens or kilns in which cores for castings or similar articles are subjected to comparatively high temperatures, and the object of the invention is to provide a furnace of this kind which is simple in construction, inexpensive to make, and more economical in the use of fuel than furnaces of the kind as heretofore constructed.

Another object of the invention is to produce a furnace of this kind in which an air blast controlled by the temperature in the oven is forced into the ash pit of the furnace, part of which passes through the grate of the furnace to aid the combustion of fuel thereon, and the remainder is by-passed at the front of the furnace in rear of the firing door to the fire box to assist in consuming combustible gases therein, from where it is discharged into a combustion chamber, where it is permitted to expand before it enters the oven.

Still another object of the invention is to provide a furnace of this kind constructed of two cylindrical parts, which is economical of space, and the inner walls of which are easily insulated and lined with refractory material.

To these and other ends, the invention consists in the construction and arrangement of parts that will appear from the following description when read in conjunction with the accompanying drawing, the novel features being pointed out in the claims at the end of the specification.

In the drawing:

Fig. 1 is a longitudinal vertical section of a furnace constructed according to one embodiment of the invention, the section being taken substantially on line 1—1 of Fig. 2 looking in the direction of the arrows, and

Fig. 2 is a plan view of the same, the top being sectioned away to expose the interior of the furnace.

Referring particularly to the drawing, in which similar reference numerals refer to the same parts in all the figures, 1 is the fire box of the furnace arranged beneath which is the ash pit 2, and at its top the fire box com-

municates with a combustion or expansion chamber 3 through an opening or flue 4. The outer wall or shell 5 of the fire box and ash pit is constructed of sheet or cast material, cylindrical in form, having its axis arranged vertically. Horizontally arranged in this cylinder is a grate 6 of usual or preferred construction which separates the fire pot from the ash pit. The parts of the grate are mounted for a swinging movement, for convenience in shaking, and to this end, they have downwardly projecting arms 7 connected to a link 8 which extends forwardly, and at its forward end is connected with an arm 9 on a shaft 10 which extends to the outside 55 of the furnace where it is provided with a crank 11 whereby it may be manually operated in the usual manner.

The cylindrical wall has openings in front of the ash pit and fire box, and over these 60 openings a metal front 12 is secured to the cylindrical casing by any suitable means. This front has the usual firing and ash pit doors mounted thereon for closing the openings therein to the fire box and the ash pit, 65 and is arranged forwardly of the fire box and grate to provide a passage 13 between the ash pit and the firebox for a purpose presently to be described. A grating 13^a is arranged over this passage at the top of the fire box. 70

The bottom 14 of the ash pit may be of concrete, and the fire box and combustion chamber are each constructed of cylindrical casings or shells which may be lined with insulating material such as mineral wool or 75 asbestos, the inner surface of which is coated or lined with highly refractory material, such as vitrifiable clay. In lining the furnace, the insulating layer is arranged therein and forms or cores of substantially the length of 80 the shells may be arranged therein before the top is placed thereon, and the lining material in a plastic state filled in between the cores and the insulation, after which the cores may be removed. To form a top, a support of 85 combustible material may be arranged on the lining formed as above, the top of which is spaced below the tops of the insulation and shells and a cover of the same material formed thereon, which cover is of sufficient thickness 90

to be self-supporting when its support is consumed. By this arrangement, expansion and contraction of the practically monolith refractory lining is freely permitted, due to the compressibility of the insulating layer arranged between it and the outer shell. The tops may also expand freely against the insulating linings between them and the outer shells. If desired, a layer of insulating material, such as sand, may be arranged on the top, as shown.

The shells 5 and 15 are arranged tangential to each other, and side walls 20 and 21 are arranged tangential thereto, forming spaces 15 22 and 23 which may also be filled in with refractory material, as shown. A furnace thus constructed is inexpensive to build, easily lined and may be quickly relined, is fully insulated, and occupies the minimum of floor 20 space.

Means are provided for forcing an air blast into the furnace. To this end, a motor driven blower 24 is provided, which is adapted to create an air current which is conducted by 25 means of a pipe 25 leading through the space 23 between the shells 5 and 15 to the ash pit into which it is discharged. It will be noted that the ash pit is substantially cylindrical in form and the lower end of the pipe is arranged to direct the air blast into it in a horizontal direction tangential thereto, so that it has a whirling motion in the ash pit. Some of this air passes through the grate, 30 supplying a forced draft and oxygen to the fire thereon. The rest of the air passes upwardly just in rear of the front 12 and in rear of the ash pit and firing doors through the passage 13, and serves to keep the front of the furnace cool, and as it rises mingles 35 with the products of combustion above the fuel on the grate in the fire box. The air and products of combustion, owing to the larger space above the fuel, expand therein to a certain extent, which tends to decrease its velocity before it is discharged into the combustion chamber 3 through the flue 4. By directing the air blast tangentially into the ash pit, a substantially uniform pressure may be obtained throughout the area of the 40 grate. The cooler air blast entering the fire box through the passage 13 is directed against the top of the fire box, and in passing absorbs the heat radiated thereto from the open fire.

45 The air which enters the fire box from the front of the furnace contains a full supply of oxygen, some of which combines with the products of combustion in the fire box to consume some of the combustible gases contained therein, which process is further continued in the combustion chamber, which permits greater expansion of the mixed air and products of combustion discharged thereto. The mixture of air and products of combustion enters at the front of the top of the com-

bustion chamber in which the volume is considerably increased by expansion and the velocity correspondingly reduced, with the result that combustion is completed therein and it is exhausted into the kiln from the bottom thereof through the flue or passageway 16 at a substantially uniform temperature, provided the pressure remains constant. The gaseous mixture entering the oven normally contains some free oxygen, which is desirable for the oxidization of some materials, such as linseed oil used in the preparation of cores.

It is desired to maintain a constant uniform given temperature in the oven or kiln. To this end, a thermostatic element 28 of usual or well known construction is arranged in the kiln or oven and controls the electric circuit to the motor 29 which drives the blower 24. The action of the heat on the 85 thermostat breaks the circuit through the motor when the temperature in the oven reaches a given maximum, and thus stops the blower and the blast, thus reducing combustion. This also reduces the flow of heat to the oven from the furnace, thus permitting the temperature in the oven to fall until a minimum temperature is reached, when the thermostat again closes the circuit through the motor to drive the blower, which creates 90 the pressure for again driving heat into the oven, and forcing a draft through the fire to increase combustion.

It will be noted that the ash pit space is 100 large in comparison to the volume of air entering the same, and that the air enters the ash pit in a horizontal direction tangential to the ash pit walls. As a result, the entering air at high velocity as it comes directly from the blower has a whirling motion imparted thereto in the ash pit where it absorbs considerable heat from the walls and by radiation, and becomes preheated before it enters the fire box through the grate, and consequently does not suddenly chill the burning 105 fuel when it comes in contact therewith. Owing to the relatively large size of the ash pit, the air is permitted to expand therein, which reduces its velocity, and it enters the grate at a relatively low velocity and uniform pressure throughout its area. By this arrangement, the fuel consumption is uniformly distributed over the grate, and the formation of clinkers, which would reduce the efficiency of 110 the fuel, is prevented.

115 It will also be noted that the forced air draft brings into the furnace a large volume of air containing oxygen in excess of that required for completely consuming the fuel in the comparatively small fire box. A comparatively large space is provided above the fire in which gases are consumed, and the forward movement of the volume of mixed air and gases is delayed, causing them to be heated to a comparatively high temperature, 120 125 130

which temperature is maintained as they pass downwardly through the combustion chamber to the oven. Under the forced draft, a large volume of heated air and gases is delivered to the oven, which quickly brings the temperature of the atmosphere in the oven to the maximum working temperature and actuates the thermostat to stop the forced draft, but under natural draft some heated 10 gases and air continues to enter the furnace.

When starting the oven, its atmosphere soon cools when the forced draft is stopped, due to the fact that the temperature of its contents is below that of its atmosphere, and 15 the forced draft is again started. Due to the fact that the contents of the oven contains a large amount of moisture which must be carried off with its atmosphere, a large volume of heated air and gas is required to maintain 20 a normal working temperature therein. A furnace constructed as herein described, having an automatically controlled forced air draft, is adapted to supply such a volume of heated gas and air from a relatively small 25 fire consuming a relatively small amount of fuel.

Although only one embodiment of the invention is shown and described herein, it will be understood that this application is intended 30 to cover such changes or modifications as come within the spirit of the invention or scope of the following claims.

We claim:

1. A furnace for a core oven comprising a 35 pair of cylindrical shells vertically arranged and tangential to each other, insulating and refractory linings in said shells, a flue connecting said shells at a point adjacent their top, a fire box in one of said shells, a grate 40 in said fire box, an ash pit under said grate, a passageway at the front of said grate between the ash pit and the fire box, a combustion chamber in the other of said shells, a flue connecting the bottom of said combustion 45 chamber with the oven to be heated, side walls arranged tangentially to said shells and secured thereto, means arranged in one of the spaces formed between said side walls and the shells for directing an air blast to the ash 50 pit, and refractory material filling said spaces and around said directing means.

2. A furnace for a core oven comprising a pair of cylindrical shells vertically arranged and tangential to each other, insulating linings of compressible material throughout the vertical height of said shells, refractory linings of plastic material inside and in contact with said insulating lining but short of said insulating lining at the top, and tops of 55 refractory plastic material arranged on said refractory lining within said insulating lining, the arrangement being such that expansion and contraction of the refractory lining is compensated for by the compressibility of 60 said insulating lining, a flue connecting said 65

shells, a fire box in one of said shells, a combustion chamber in the other of said shells, and a flue connecting said combustion chamber with the oven to be heated.

In witness whereof, we have hereunto signed our names.

JASPER B. WILLSEA.
THOMAS A. KENNEDY.
